DESIGN FOR A TRANSFORMER CABINET

Arthur Charles Haggstrom, Rockford, Ill., assignor to Jefferson Electric Company, Bellwood, Ill., a corporation of Illinois

Application August 26, 1935, Serial No. 58,598

Term of patent 7 years

To all whom it may concern:

Be it known that I, Arthur Charles Haggstrom, a citizen of the United States, residing at Rockford, in the county of Winnebago, in the State of Illinois, have invented a new, original, and ornamental Design for a Transformer Cabinet, of which the following is a specification, reference being had to the accompanying drawing, forming part thereof.

The figure is a perspective view of a transformer cabinet composed of a series of planes which, in transaxial section, form the outline of a hexagon.

I claim:

The ornamental design for a transformer cabinet as shown and described.

ARTHUR CHAS. HAGGSTROM.
